SAFETY DEVICE FOR WINDOWS

Filed Aug. 25, 1922

WITNESS

P.F. Dilworth

INVENTOR
August Cobbell

By Jack R. Snyder
Attorney

UNITED STATES PATENT OFFICE.

AUGUST COBELL, OF PITTSBURGH, PENNSYLVANIA.

SAFETY DEVICE FOR WINDOWS.

Application filed August 25, 1922. Serial No. 584,273.

To all whom it may concern:

Be it known that I, AUGUST COBELL, a citizen of the United States, residing at Pittsburgh, in the county of Allegheny and 5 State of Pennsylvania, have invented certain new and useful Improvements in Safety Devices for Windows, of which the following is a specification.

This invention relates to a safety device 10 for windows, and the primary object of the invention is to provide a safety device of the character described, in a manner as herein-after set forth, which is adapted to be permanently fixed to the window frame to 15 provide full protection to persons working at the outside of the window for cleaning the same or for any other purposes, particularly when such windows are positioned at some height from the ground.

Further important objects of the invention 20 are to provide a safety device of the type stated, which may be readily attached to a window frame of any construction without the use of any special materials except 25 those embodied in the invention itself, which is simple in its construction and arrangement, strong, durable and efficient in its use, collapsible when not in use, and comparatively inexpensive to manufacture.

With the foregoing and other objects in view, which will appear as the description proceeds, the invention resides in the combination and arrangement of parts and in the details of construction hereinafter described and claimed, it being understood 35 that changes in the precise embodiment of the invention herein disclosed can be made within the scope of what is claimed without departing from the spirit of the invention.

In the drawing forming a portion of this specification and wherein like numerals of reference designate corresponding parts throughout the several views:—

Figure 1 is a perspective view of a window having my improved safety device attached thereto.

Figure 2 is a fragmentary vertical view of the inner face of a window frame illustrating the attachment of the supporting 50 brackets and the platform.

Figure 3 is an enlarged perspective view of the supporting bracket.

Figure 4 illustrates the platform and guard in the folded position.

Referring in detail to the drawing 1 and 2 denote, respectively, the upper and lower

sashes of a window of the ordinary construction. The sashes are mounted in the usual window frame including the respective vertical side members 4 and 5 and the window 60 sill 6.

Fixedly secured to the inner face of each of the vertical side members 4 and 5, by means of the countersunk screws 7, is a forwardly projecting supporting bracket 8, substantially triangular in contour. The brackets 8 on respective side members 4 and 5 are disposed in parallelism relatively to each other.

The lower end of each of the brackets 8 is 70 turned inwardly to form a groove 9 which extends along the entire lower edge of each of the brackets 8 with the exception of the rear portion 10. The latter extends below the groove 9 on the an even vertical plane 75 and is provided with apertures 11 for the reception of the securing screws 7.

The inner face of the rear portion 10 of each of the brackets 8 is slightly depressed 80 relatively to the plane of the inner face 12 of the projecting portion of the bracket 8, for the purpose to be described.

A substantially U-shaped guard rail 13 has the end of each its arms pivotally connected to the rear portion 10, of a respective 85 bracket 8, by means of the screw 14, which latter extends through the aperture 15 provided therefor in each of the brackets 8. As the rear portion 10 of each of the brackets 8 extends on an even plane below the groove 90 9, ample clearance is provided to permit of the shifting of the guard rail 13 without interfering with the groove 9 formed on the lower edge of the bracket 8.

When the guard rail 13 is in the extended 95 position for use, as shown in Figure 1, of the drawing, the rear portion of the arms will rest in the grooves 9, of respective brackets 8, and hold the guard rail 13 in the horizontal position, as illustrated in the figure referred to.

When not in use, the guard rail 13, may be folded upwardly so that the arms thereof will extend parallel with respective vertical side members 4 and 5 of the window frame. 105 While in this position the ends of the arms of the guard rail 13 will extend in the depressed rear portions 10 of the brackets 8, the offset projecting portions of the brackets 8 preventing liability of the guard rail 13 110 falling by gravity from such folded position, as the guard rail springs into place by

its frictional engagement with the brackets 8 during the folding operation.

A platform 15 for use in connection with the guard rail 13 is provided and is supported by a pair of transversely disposed bars 16, having their rear ends formed to provide hooks 17 adapted to engage the sill 6 of the window frame. The forward ends of the bars 16 are pivoted, as at 17', to the vertical guard bars 18 by means of the elongated rod 19. The upper ends of the guard bars 18 are connected by an elongated rod 20.

A plurality of hangers 21 connects the platform 15 with the guard rail 13. The lower ends of each of the hangers 21 is pivotally connected, as at 22, to the rod 18, and the upper ends of the hangers 21 are formed to provide hooks 23 adapted to detachably engage the guard rail 13. The rod 20 is riveted to the hangers 21.

A guard 24, preferably constructed from wire mesh, is carried by the rods 18 and 20, and covers the entire space therebetween.

The platform 15 and guard 24 may be flatly folded together when not in use as clearly illustrated in Figure 4, of the drawing.

The brackets 8 and guard rail 13 are intended to be permanently fixed to the window frame, but the platform 15 with associated parts is adapted to be detachably connected therewith, to permit of its use with any windows provided with my improved guard rail 13.

The position of the guard rail 13, relatively to the window frame, may be varied to best meet conditions found in practice.

By the use of my improved safety device persons engaged on windows at a height may conveniently work and move about without the danger usually attending such operations.

What I claim is:—

1. A safety device for the purpose set forth comprising the combination with a window frame, of a pair of supporting brackets carried by said window frame, and a guard rail pivotally connected to said

brackets, said brackets having their rear portions offset adapted for the reception of said guard rail for securing said guard rail in the inoperative or collapsed position.

2. A safety device for the purpose set forth comprising the combination with a window frame, of a pair of supporting brackets carried by said window frame, a guard rail pivotally connected to said brackets, said brackets including means for securing said guard rail in the inoperative position, and a platform including a guard detachably connected with said window frame and with said guard rail.

3. A safety device for the purpose set forth comprising the combination with a window frame, of a pair of supporting brackets carried by said window frame, a guard rail pivotally connected to said brackets, said brackets having their rear portions offset adapted for the reception of said guard rail for securing said guard rail in the inoperative or collapsed position, and a platform including a guard detachably connected with said window frame and with said guard rail.

4. A safety device for the purpose set forth comprising the combination with a window frame, of a pair of triangularly shaped supporting brackets carried by said frame, a substantially U-shaped guard rail having its arms pivotally connected with said brackets, each of said brackets having a portion of its lower edge formed to provide grooves adapted for the reception of said guard rail arms for securing the said guard rail in the extended or operative position, said brackets further formed with depressed rear portions adapted for the reception of the guard rail arms for securing the guard rail in the collapsed or inoperative position, and a collapsible platform including a guard element pivotally connected with said platform, adapted to be detachably connected to said window frame and with said guard rail.

In testimony whereof I affix my signature.

AUGUST COBBELL.
